UNITED STATES PATENT OFFICE.

WALTER L. BISSELL, OF CLEVELAND, OHIO.

SCHOOLROOM-CHECKER.

1,347,888.

Specification of Letters Patent. Patented July 27, 1920.

Application filed May 7, 1920. Serial No. 379,525.

To all whom it may concern:

Be it known that I, WALTER L. BISSELL, a citizen of the United States, resident of Cleveland, county of Cuyahoga, and State 5 of Ohio, have invented new and useful Improvements in Schoolroom - Checkers, of which the following is a specification, the principle of the invention being herein explained and the best mode in which I have 10 contemplated applying that principle, so as to distinguish it from other inventions.

My invention relates to school room checkers, and particularly to devices of this character which will enable the person in charge 15 to check the attendance in the room. The object of the invention is to provide simple and inexpensive means whereby this function may be performed accurately and quickly in crowded moments or at a rush pe- 20 riod.

The annexed drawings and the following description set forth in detail certain means embodying my invention, the disclosed means, however, constituting but one of the 25 various mechanical forms in which the principle of the invention may be employed.

In said annexed drawings:

Figure 1 represents a top plan view of my new and improved checker; showing in 30 dotted lines an open position of certain spring fingers;

Fig. 2 represents a front elevation, showing a seating plan best adapted for a study hall or grade school;

Fig. 3 represents a bottom plan view, showing in dotted lines an open position of certain other spring fingers;

Fig. 4 represents a rear elevation of a certain filler pad;

Fig. 5 represents a transverse vertical section taken in the planes indicated by the lines V—V, Figs. 2 and 3, showing, however, one set of spring fingers in open position;

Fig. 6 represents a front elevation of the 45 seating plan shown in Fig. 2; and

Fig. 7 represents a front elevation of a seating plan adapted to be portrayed upon the reverse side of the plan shown in Fig. 6 or, if desired, portrayed upon an entirely 50 different card, said plan being utilized for checking attendance in a home room and at various classes held in said room. This view is shown upon a scale one-half size, and is of a type of plan portrayed upon an inde- 55 pendent card.

Referring to the annexed drawings, the

principal elements of my new and improved checker are, a base or holder, indicated by the ordinal 1, a filler pad of any suitable number of sheets of separable highly transparent tracing paper indicated by the ordinal 2 and a seating plan indicated by the ordinal 3. The filler pad is adapted to be secured at one edge to the base 1 by means of certain fingers 4 made of polished spring wire and secured at one end in the base 1 and adapted at their free ends to be snapped over the front of the filler pad, as plainly shown in Fig. 2. The specific means for securing the free ends of these spring fingers 4 over the pad 2 consists in bent finger ends 4' adapted to intersect eyelets 7 connecting together the two arms 6' of clips 6, U-shaped in cross-section, and receiving between said arms the pad of filler sheets, said eyelets 7 passing through said pad, all as plainly shown in Fig. 5.

A second pair of spring fingers 5 are also secured at one end in the base 1, the same being secured at the edge of the filler pad opposite the edge near which said spring fingers 4 are secured, said spring fingers 5 serving to hold the topmost filler sheet 9 and the seating plan 3, at their bottom edges against displacement or relative movement. 85 When it is desired to insert a seating plan or to remove the same, the spring fingers 5 are lifted from the pad and adjusted to the position shown in dotted lines in Fig. 3. See also Fig. 5. Notches 3' formed in the base 90 1, filler pad 2, and seating plan 3 enable the spring fingers 5 to be easily grasped by the thumb and forefinger.

The seating plan, referring particularly to Figs. 2 and 6, consists of a suitable durable card 3, properly sized to the support 1, and ruled to display any suitable number of distinct rectangular spaces upon which are displayed indicia of the proper relative seating of the several pupils which should be present, these indicia consisting preferably of the several pupils' names. In order that the seating plan may be properly positioned upon the base 1, the card 3 is formed with upper recesses or notches 3' 100 which receive the paper compressed between the clip arms 6' thus properly relatively alining the pad 2 and seating plan.

Referring to Fig. 7, the seating plan 10 therein shown may be the one portrayed 110 upon the reverse side of the plan shown in Fig. 6, or, as actually shown in said figure,

may be an entirely different card, the same being shown as about one-half size and having a plurality of sections indicated by *a*, *b*, *c*, etc., this plan being utilized in what is 5 known as a home room for pupils or headquarters of a specific teacher, the section *a* displaying the names of the pupils of that particular room, and the sections *b*, *c*, *d*, etc., displaying the names of the pupils comprising 10 the several classes that report for recitation in that room during the day. The use of the checker including this seating plan shown in Fig. 7 will be as follows: Said plan 10 is inserted under the topmost 15 transparent filler sheet 9 and, so soon as school is called in the morning, quickly the teacher in charge of this home room will note upon said filler sheet, over the names of the absent pupils, a suitable indication of 20 such absence, preferably simply a check mark, as shown in said Fig. 7. This is effected quickly and accurately, as will be well understood. This report is sent to the office at any convenient time. The office 25 posts this information or distributes the same to the various study rooms in which the seating plan shown in Figs. 2 and 6 is utilized. The pupils whose names appear upon section *a* of Fig. 7, of course, quickly 30 distribute themselves through the building in the home rooms of other teachers, in recitation rooms or headquarters, or in the study room, and other classes come to the first room for recitation in special branches, 35 the names of the pupils of such other classes being indicated upon the sections *b*, *c*, *d*, *e*, *f*, etc., according to the number of classes. The teacher in charge of the headroom covered 40 by the seating plan 10, checks the names of the absentees from the several classes *b*, *c*, *d*, etc.

In the event of the use of the seating plan shown in Fig. 2, in a grade school, for 45 instance, the checks upon the students' attendance cover the whole day and may include such indications as a large "A" denoting absence in the morning, and a large "P" denoting absence in the afternoon, or these marks and other indications of intervals of less than one-half day may be utilized. Instances of such checking are shown in Fig. 2. In the use of such a plan for a study room, the teacher in charge of 50 the room checks the absentees, using different colored checks or other varying insignia to indicate absence in more than one study period.

The teachers in the respective headrooms 55 and in the study rooms, at the end of the day, or at any other suitable and convenient period, compare their checks upon the several classes with the report which has been posted by or come from the office concerning the several pupils. Where absentee

checks correspond with absentee reports from the office, no further report is made upon these names. If, however, absence from the headroom combined with presence in one or more classes, or presence in the 70 headroom combined with absence from one or more classes, is shown to be the record of a pupil, or other irregularity appears, the same is reported.

When a teacher serves in a headroom and 75 classroom as well as in a study hall and checks attendance in both rooms and wishes to use but one card, seating plans for the two rooms are arranged upon the two sides of the card and the card reversed, as necessary, only one filler sheet being used, if desired, by making the checks for the two rooms upon the filler sheet in different colors or otherwise differentially noted.

When the proper checks upon the filler 80 sheet 9 have been posted or transferred to permanent records, by the teacher in charge or by the office where the report may be sent, the checked filler sheet is removed, after loosening the spring fingers 5, and destroyed; the seating plan 3 is detached from the base 1, inserted under the next lower transparent sheet of the filler pad 2, and the fingers 5 fastened.

The merits of my invention are that it is 95 simple, accurate, compact, adaptable and inexpensive, and saves time and brain energy at a period of school activity when the moments are most crowded and there is need for most despatch in getting the work of 100 the school under way.

I do not wish to limit myself to the use of my improved checker in school rooms only, inasmuch as the same will lend itself 105 for convenient and desirable use in any situation where it is essential quickly and accurately to check an attendance.

What I claim is:

1. In a school-room checker, the combination of a base or holder; a filler pad of 110 separable transparent sheets secured thereto; and a seating plan inserted beneath a transparent sheet and secured against movement relative to said sheet.

2. In a school-room checker, the combination of a base or holder; a filler pad of separable transparent sheets secured thereto, said sheets being held to said pad by eyelets in the pad and spring fingers intersecting 115 said eyelets; and a seating plan inserted beneath a transparent sheet and having notches or recesses adapted to receive said eyelets.

3. In a school-room checker, the combination of a base or holder; a filler pad of 120 separable transparent sheets secured thereto; and a card displaying upon both sides indicia of the correct relative positions of the pupils, said card adapted to be inserted 125 130

beneath a transparent sheet and secured against movement relative to said sheet.

4. In a school-room checker, the combination of a base or holder; a transparent sheet secured thereto; and a card adapted to be inserted beneath said transparent sheet and secured against movement relative to said sheet, said card being provided upon its two sides with indicia of different correct 10 relative positions of pupils.

5. In a school-room checker, the combination of a base or holder; a filler pad of separable transparent sheets secured together at

one edge by clips, U-shaped in cross-section and having eyelets intersecting the pad; 15 spring wires secured to said base and adapted to intersect said eyelets; a seating plan inserted beneath a transparent sheet and having notches or recesses adapted to receive said eyelets; and other spring wires 20 secured to said base and adapted to have tension against said pad and seating plan at the edge of said pad opposite to said eyelets.

Signed by me, this 1st day of May, 1920. 25
WALTER L. BISSELL.
